UNITED STATES PATENT OFFICE

WILLIAM F. REACH, OF SPRINGFIELD, MASSACHUSETTS, ASSIGNOR TO A. G. SPALDING & BROS., OF NEW YORK, N. Y., A CORPORATION OF NEW JERSEY

GOLF CLUB WITH METALLIC SHAFT AND HOSEL

Original application filed July 6, 1928, Serial No. 290,823. Divided and this application filed April 8, 1929. Serial No. 353,521.

This specification is a division of that filed by me July 6, 1928, No. 290,823, and concerns a specific form of the invention therein disclosed.

5 The invention consists in the features hereinafter described and pointed out in the claims.

In the accompanying drawing is shown a part side elevation and a part vertical sectional view of an iron embodying my invention.

The invention provides a club having a metal shaft or handle secured to a metal hosel by means which, while holding the club head 15 permanently to the shaft, will yet permit the desired torsional cushioning effect.

The numeral 1 indicates the club head, which is representative of any type, such as a mid-iron, mashie, a metal club head of the 20 driver type, or any head having a metal hosel. 2 indicates the tubular steel shaft of customary form.

The bore of the hosel 1a is made sufficiently larger in internal diameter to provide a space between it and the shaft when the latter is inserted, which space is designed to receive a sleeve 3 of distortable material. Preferably the shaft end and bore are made cylindrical, the latter being of larger 25 diameter as stated, but this cylindrical feature is not material, as they might be made with a slight taper without departing from the spirit of my invention.

Prior to the insertion of the shaft end 30 in the bore of the hosel, the sleeve of distortable material is placed on the shaft end.

The material I prefer to use for the sleeve is rubber, which may be vulcanized on the shaft, or secured thereto by a suitable cement, 35 whereby it is caused to adhere to the shaft, whereafter the end of the latter is inserted in the bore of the hosel, which is of such a size as to enable the shaft end and sleeve to be inserted therein with a driving fit.

40 The rubber sleeve, it will be observed, does not extend to the upper end of the hosel, but on the contrary, the hosel is long enough, compared to the length of the sleeve, to extend beyond the upper end of the sleeve, and thus there is provided a projecting por-

tion of the hosel which at its upper end surrounds the shaft.

After the shaft with the sleeve of distortable material is fitted into the hosel, the upper thinned or tapered end of the hosel is 55 subjected to pressure and is thereby caused to contract. This makes the bore of the hosel at its upper or outlet end of smaller diameter than the diameter of the bore at points intermediate its ends. 60

It will be noted that the hosel is tapered exteriorly from about point B to its upper end A, and the thus thinned upper end readily may be reduced in external and internal diameter by the rolling or die action. 65

In this reduction the upper end of the hosel contacts with the shaft at a point above but adjacent the end of the rubber sleeve. This will lock the head onto the shaft, and resist any tendency for the head and shaft 70 to be relatively displaced in a direction lengthwise of the club. For obtaining the proper degree of torque, reliance is had upon the initial frictional grip of the rubber sleeve upon the interior wall of the hosel. 75

As an example of one relation of the parts, it may be said that the diameter of the lower or small end of the shaft may be, say, .355". The taper may be .092" per foot. The hosel may be reamed with a straight reamer to 80 make a cylindrical bore. The rubber sleeve is cylindrical exteriorly to fit this bore.

Instead of the above dimensions and form, I may, for instance, use a shaft of the above dimensions and form, with a rubber sleeve tapered exteriorly to correspond to the taper of the shaft, i. e., .092" per foot, and the bore of the hosel is reamed with a taper reamer so that it tapers towards the lower end in conformity with the taper of 90 the rubber sleeve and shaft. 85

I claim:

1. In a golf club and in combination, a head having a metallic hosel, a metal shaft, a sleeve of torsionally distortable resilient 95 material fixed to the shaft, and fitting against the interior of the wall of the hosel, the upper end of the hosel extending along the shaft above the upper end of the sleeve and having its bore contracted at said upper end 100

with the wall of said bore overlying the end of the sleeve, said sleeve being of rubber material vulcanized to the shaft, said vulcanized shaft and rubber sleeve being inserted 5 into the hosel from the upper end thereof.

2. A golf club having a head and a metal hosel in one piece throughout, a metal shaft, and a sleeve of distortable resilient shock absorbing material prefixed to said shaft and 10 inserted with said shaft as one body into said hosel from the upper end thereof with a driving fit contact with the wall of the hosel, said hosel extending above the upper end of the sleeve and having its wall bodily compressed at a point above the sleeve to overlie 15 the upper end of the same, substantially as described.

In testimony whereof, I affix my signature.
WILLIAM F. REACH.
